MODERNISTIC TABLE LAMP

Charles W. Clemens, Nashville, Tenn., assignor to Aladdin Industries, Incorporated, Nashville, Tenn., a corporation of Illinois

Application August 2, 1954, Serial No. 31,693

Term of patent 3½ years

(Cl. D48—20)

FIG. 1.

To all whom it may concern:

Be it known that I, Charles W. Clemens, a citizen of the United States, residing at Nashville, county of Davidson and State of Tennessee, have invented a new, original, and ornamental Design for Modernistic Table Lamp, of which the following is a specification, reference being had to the accompanying drawing, forming part thereof, in which

The dominant features of my design are shown in solid lines.

I claim:

The ornamental design for a modernistic table lamp, as shown and described.
